HERMANN V. FENGLER, OF PHILADELPHIA, PENNSYLVANIA, AND VICTOR B. ROUILLOT, OF MAYS LANDING, NEW JERSEY, ASSIGNEES TO UNDERWOOD TYPEWRITER COMPANY, OF NEW YORK, N. Y., A CORPORATION OF NEW JERSEY.

TYPE-WRITING MACHINE.

1,079,548.

Specification of Letters Patent. Patented Nov. 25, 1913.

Application filed August 28, 1909. Serial No. 514,995.

To all whom it may concern:

Be it known that we, HERMANN V. FENGLER, a citizen of the United States, residing in Philadelphia, county of Philadelphia, and State of Pennsylvania, and VICTOR B. ROUILLOT, a citizen of the United States, residing in Mays Landing, county of Atlantic, and State of New Jersey, have invented certain new and useful Improvements in Type-Writing Machines, of which the following is a specification.

This invention relates to typewriting machines, the object being to provide means for printing a dotted or a substantially continuous line partway or entirely across the paper.

This invention provides means whereby the operator, by simply actuating a key or finger-piece, can effect the imprint of a dotted line, a continuous line or the continued repetition of a character or letter, as "x" for example. The type is brought to the printing point, and at the same time releases the carriage to permit it to travel while the type is continuously or repeatedly printing.

To print a dotted line, the type is mechanically vibrated repeatedly to and from the printing point. The type carrier is controlled by a special key, which throws the type bar to printing position, effects the release of the power driven carriage, and causes the carriage to actuate the type-bar vibrative mechanism.

The ribbon is fed during the time the type is at the printing point, to prevent puncture or tearing of the ribbon and to permit clear impressions being made.

The improvements are shown applied to the Underwood style of front strike type-writing machine. There is provided a bipartite type carrier, its parts yieldingly connected, one part or arm being connected to and operated by a key in the usual manner. The remaining part constitutes the type bar proper, having the type on its free end. The type bar part or section is provided with an actuating tongue, which, when the type carrier is thrown to printing position, is engaged by the teeth of a star or cam wheel, the latter actuated by the carriage, by means of a rack thereon, meshing with a pinion that is connected to the star wheel. Said rack is normally idle, but is thrown into working position by said key. The star

wheel intermittently forces the type bar away from the printing point, against the tension of a spring so that when the tongue slips off the point of one of the teeth, the spring swings the type bar toward the paper to print again.

In the accompanying drawings, Figure 1 is a vertical cross sectional view through the Underwood type of front strike machine illustrating one embodiment of our invention, the parts being in normal inactive position. Fig. 2 is a fragmentary front view, showing the parts in active position. Fig. 3 is a perspective detail view of the vibrating mechanism. Fig. 4 is a perspective detail view showing the type-carrier in printing position engaged with the vibrating mechanism just prior to the imprint of the type. Fig. 5 is a fragmentary detail perspective view of the star wheel and type carrier, illustrating the position of the carrier parts at the moment of making an impression. Fig. 6 is a detail view illustrating a preferred type on the type bar.

1 indicates the frame of the Underwood type of front strike machine, 1 being a rail on which slides the carriage 2, carrying a platen 3. The carriage is driven by means of a spring barrel 50 connected through a belt 51 to the carriage. Arms 4^a pivoted at 4 to the carriage carry a letter-spacing rack 5 normally engaged by an escapement, indicated at 6, and releasably held in such engagement by a spring 7 extending between a release key 8 and a stationary point on the carriage. A tabular stop-supporting frame, a fragment of which is indicated at 9, is mounted upon a shaft 10 pivoted in the frame, the shaft having a finger 11 to actuate a lever 12 carrying a roll 13 engaging the letter space rack 5 to release the latter from the escapement. The shaft 10 is rocked to effect such disengagement by a key-controlled lever 22 connected by a link 15 to the shaft. A ribbon 16 is wound on spools 17 on spool shafts 18, driven by a shaft 19, carrying a ratchet 20 engaged by a detent 21. A finger piece or key 23 forms one of the keys of the keyboard, and is designed to operate printing devices and carriage-releasing and related devices. The key 23 is carried by the usual spring-actuated pivotally-mounted key lever 24, a sub-

lever 25 pivoted at 26 connecting the key lever, at a point intermediate its ends, with a type carrier pivotally supported in the usual slotted segment 27.

5 For dotted and dash lines, it is desirable that the type be held yieldingly at the printing point, to accomplish which there is provided a bipartite type carrier consisting of an arm 28 to which the sub-lever is connected, and a type bar 29, pivotally secured to the arm at 30, and held yieldingly against a stop 31 on the arm, by a spring 32 carried by the arm and engaging the type bar which carries the type 33.

10 Preferably the type consists of the period, and the hyphen or underscore, as shown in Fig. 6, but other characters or letters might be substituted therefor.

15 The type bar 29 has an actuating tongue 34, extending through an aperture 35 in the segment, to be engaged by the teeth of a dished star or cam wheel 36 supported on a shaft 37 journaled in the frame, which shaft also carries a pinion 38, which rotates the star wheel to bring its teeth successively into engagement with the tongue, to crowd or shoulder the tongue and type bar outwardly against the tension of the spring 32. By crowding the type bar outwardly in this manner, the type is carried 20 away from the paper; against which, however, it is again thrown by the spring 32 as soon as the tongue slips off the point or crown of one of the teeth on the revolving star wheel.

25 It will be seen that the star wheel serves temporarily as an escapement wheel for the power-driven carriage, and that the tongue 34 is an escapement pallet, whereby the carriage is permitted to feed a step at a time, so that the impressions made by the type appear in regular succession upon the paper. In this manner, the type is repeatedly oscillated from and toward the paper after its 30 first imprint caused by the actuation of the key 23, so that a dotted or a dash line is formed.

35 To revolve the star wheel and pinion, a rack 39 is attached to the carriage preferably to the swinging arms 4^a, whereby, when the letter-spacing rack 5 is released from its escapement, the vibrator rack 39 by the same action, is thrown into mesh with its pinion 38. As soon as the carriage is released from 40 its escapement, it is free to travel under the impetus of its spring drive, and by the engagement of the vibrator rack 39 with the pinion 38, the latter, together with the star wheel, is rotated to vibrate the type bar. 45 These movements of the racks are effected by the key 23, which has a l. k 40, overhanging the carriage-releasing lever 22, so that a depression of the key 23 to throw the type carrier to printing position, will 50 also cause the finger 11 to turn the lever 12

which releases the letter-spacing rack, and engages the vibrator rack 39 with the pinion 38.

55 The ribbon feed may comprise a suitably journaled lever 41, one end of which passes through an inclined slot 42 in a guide plate 43 and is operatively connected with, or formed into, a pawl 44 conveniently engaging the ratchet wheel 20 on the ribbon drive shaft 19, the inclined slot permitting the pawl to follow the ratchet throughout its stroke. The opposite end of the lever is formed into, or has secured thereto, a tappet 45 normally received in a recess 46 in the arm 28 when the type carrier is in printing position, such recess being at least partially covered or overlapped by the type bar 29 when the latter is in normal position against the stop 31. A spring 47 tends to project the tappet 45 into the recess in the arm, which recess is uncovered or opened each time a tooth on the star wheel forces the type bar 29 outward away from the paper and relative to the arm 28. When the type bar is returned toward the paper by the action of its spring 32, it engages the tappet and forces the latter out of the recess 46 against the tension of spring 47, thereby actuating the lever 41 to cause the pawl 44 to feed the drive shaft step by step to keep the ribbon moving across the line of travel of the type.

60 Variations may be resorted to within the scope of the invention, and portions of the improvements may be used without others.

65 Having thus described our invention, we claim:

1. In a typewriter, the combination with a carriage, and an escapement normally engaged thereby, of a type-carrier movable to printing position, and a release lever actuated through the operation of the carrier for disengaging the carriage from its escapement and maintaining it in such disengaged position, when the type-carrier is in printing 110 position.

2. In a typewriter, the combination with a power-driven carriage, and an escapement normally engaged thereby, of a key-operated type-carrier, and a release lever actuated by the key for disengaging the carriage from its escapement to permit it to feed continuously while the type is at the printing point.

3. In a typewriter, the combination with a power-driven carriage, and an escapement normally engaged thereby, of a key-operated type-carrier movable to printing position, a release actuated by the key for disengaging the carriage from its escapement to permit it to feed continuously while the type-carrier is in printing position, and mechanism for feeding the ribbon while the type-carrier is in printing position.

4. In a typewriter, the combination with a carriage, of a yielding manually-operated

- type-carrier, and means actuated through the travel of the carriage in letter-feeding direction to bodily vibrate said type-carrier repeatedly to make a line of impressions.
5. In a typewriter, the combination with a power-driven carriage, and an escapement normally engaged thereby, of a key, a type-carrier movable by said key, and means actuated by said key for disengaging the carriage from its escapement to permit it to feed continuously while the type is at the printing point, and means to enable the carriage to vibrate said type-carrier.
10. 6. In a typewriter, the combination with a power-driven carriage, of a yielding or resilient type carrier, a rotary element from which the carrier is actuated when in printing position for causing the carrier to repeatedly oscillate to effect the imprint of a plurality of successive type impressions across the page, and mechanism for feeding the ribbon while the type-carrier is being operated by the carriage.
15. 7. In a typewriter, the combination with a power-driven carriage and an escapement with which the carriage is normally engaged, of a yielding or resilient type-carrier, a rotary element from which the carrier is actuated when in printing position for causing the carrier to repeatedly oscillate to effect the imprint of a plurality of successive type-impressions, and a release operated by the actuation of the type-carrier to printing position for disengaging the carriage from its escapement and maintaining such disengagement while the carrier remains in printing position.
20. 8. In a typewriter, the combination with a carriage, and an escapement normally engaged thereby, of a type carrier, a release actuated by the operation of the type carrier to printing position, to disengage the carriage from its escapement and permit free feed of the carriage, and mechanical means for effecting repeated vibrations of the type-carrier while in printing position, to make a plurality of successive type-impressions.
25. 9. In a typewriter, the combination with a carriage, and an escapement normally engaged thereby, of a type carrier, a release actuated by the operation of the type carrier to printing position, to disengage the carriage from its escapement and permit free feed of the carriage, mechanical means for effecting repeated vibrations of the type-carrier while in printing position, to make a plurality of successive type impressions, and a ribbon feeding mechanism operative when the carrier is in printing position.
30. 10. In a typewriter, the combination with a carriage, and an escapement normally engaged thereby, of a type carrier, a release actuated by the operation of the type carrier to printing position, to disengage the carriage from its escapement and permit free feed of the carriage, mechanical means for effecting repeated vibrations of the type-carrier while in printing position, to make a plurality of successive type impressions, and a ribbon feeding mechanism operated by the carrier when in printing position.
35. 11. In a typewriter, the combination with a type-carrier, of mechanical means for causing the carrier to repeatedly vibrate while in printing position to effect the imprint of a plurality of successive type-impressions, ribbon-feeding mechanism, and means for automatically operating the latter while the type is being operated.
40. 12. In a typewriter, the combination with a carriage and an escapement normally engaged thereby, of a key-operated type-carrier, a release actuated through the operation of the key for disengaging the carriage from its escapement, and vibrative mechanism rendered operative while the carrier is in printing position for repeatedly vibrating the carrier to effect the imprint of a plurality of successive type-impressions.
45. 13. In a typewriter, the combination with a carriage, and an escapement therefor, of a key-operated type-carrier, a release operated by the actuation of the key for permitting the carriage to be fed independently of the escapement, and carriage-actuated vibrative mechanism for repeatedly vibrating the type-carrier to effect the imprint of successive type-impressions.
50. 14. In a typewriter, the combination with a power-driven carriage and an escapement therefor, of a key-operated type-carrier, vibrative mechanism for imparting a series of oscillations to the type-carrier when in printing position, to cause the type carried thereby to effect the imprint of successive impressions, and a release actuated by the type-carrier key for disengaging the carriage from its escapement and engaging it with the vibrative mechanism to effect the operation of the latter.
55. 15. In a typewriter, the combination with a power-driven carriage and an escapement therefor, of a key-operated type-carrier, vibrative mechanism for imparting a series of oscillations to the type-carrier when in printing position, to cause the type carried thereby to effect the imprint of successive impressions, and a release actuated by the key for disengaging the carriage from its escapement, to permit it to be fed while the type is at the printing point.
60. 16. In a typewriter, the combination with a carriage, of a key-operated type-carrier, vibrative mechanism for mechanically imparting a series of oscillations to the type-carrier when in printing position, to cause the type to effect a plurality of successive impressions, and a ribbon feeding mechanism actuated by the type carrier.
65. 17. In a typewriter, the combination with a carriage, of a key-operated type-carrier, vibrative mechanism for mechanically imparting a series of oscillations to the type-carrier when in printing position, to cause the type to effect a plurality of successive impressions, and a ribbon feeding mechanism actuated by the type carrier.

- 4
1. A carriage, of a key-operated type-carrier, carriage-actuated vibrative mechanism for repeatedly oscillating the carrier when in printing position, to cause the type to effect a plurality of successive impressions, and ribbon-feeding mechanism actuated by the type carrier when in printing position. 5
2. In a typewriter, the combination with a carriage, and letter-spacing mechanism engaged thereby, of a type-carrier mechanism normally disconnected from the carriage for oscillating the type-carrier bodily when at the printing point, and a key-controlled lever having means for moving the type-carrier to the printing point and also having means for disconnecting the letter-spacing mechanism from the carriage and effecting a connection between the carriage and the oscillating mechanism. 10
3. In a typewriter, the combination with a type-carrier having a type, a key or finger-piece connected with the carrier for actuating the type-carrier to the printing position of vibrative mechanism rendered effective solely by the operation of the key or finger-piece to repeatedly oscillate the type carrier while in printing position. 15
4. In a typewriter, the combination with a carriage, a type-carrier provided with a type, and a key or finger-piece connected with the carrier for actuating the type to printing position, of vibrative mechanism for repeatedly oscillating the type while in printing position, and an actuator on the carriage for operating the vibrative mechanism, such actuator being rendered effective solely by the actuation of the key or finger-piece. 20
5. In a typewriter, the combination with a power-driven carriage, and an escapement therefor, of a type-carrier having a type, vibrative mechanism for repeatedly oscillating the type while at the printing point, an actuator on the carriage for operating the vibrative mechanism, and a key or finger-piece connected with the type-carrier for throwing the type to the printing point, and for effecting the disengagement of the carriage from its escapement, and for engaging the actuator on the carriage with the vibrative mechanism. 25
6. In a typewriter, the combination with a power driven carriage, of a type-carrier having a type, a key connected with the carrier for actuating the type to the printing point, and vibrative mechanism actuated by the carriage during the letter-feeding movement thereof and rendered effective solely by the operation of the key, to repeatedly oscillate the type while at the printing point. 30
7. In a typewriter, the combination with a type-carrier actuating mechanism, of a type-carrier including an arm operated by the carrier actuating mechanism, a type bar mounted on the arm for movement independently thereof, a spring for yieldingly re-
- taining the type bar in a predetermined position relative to the arm, and a vibrative mechanism for intermittently oscillating the type bar while it is in printing position against the tension of the spring. 70
8. In a typewriter, the combination with type-carrier-actuating mechanism, of a type-carrier including an arm connected to the carrier-actuating mechanism, a type bar pivoted to the arm and carrying a type, a stop on the arm against which the bar is yieldingly held by a spring, and a vibrative mechanism with which the type bar is operatively engaged when in printing position for intermittently swinging the type bar against the tension of its spring. 75
9. In a typewriter, a type-carrier having a type, vibrative mechanism for repeatedly oscillating the type while at the printing point, a key connected with the carrier for holding the type yieldingly to the printing point, and ribbon-feeding mechanism actuated by the type bar. 80
10. In a typewriter, a type-carrier having a type, vibrative mechanism for repeatedly oscillating the type while at the printing point, a key connected with the carrier for holding the type yieldingly to the printing point, a ribbon-winding mechanism including a tappet, the type carrier being recessed to accommodate the tappet, which is intermittently engaged by the type bar to feed the ribbon during the oscillation of the type. 85
11. In a typewriter, the combination with type-carrier-actuating mechanism, of a type-carrier including a recessed arm operatively connected to the carrier-actuating mechanism, and a type bar carrying a type and mounted for independent movement on the arm, a spring for yieldingly maintaining the type bar in a predetermined position relative to the arm, in which position the type bar overlaps the recess in the arm, vibrative mechanism with which the type bar operatively engages when in printing position for imparting repeated oscillations to the type bar, and ribbon-winding mechanism including a tappet, and a pawl and ratchet mechanism operated thereby to wind the ribbon, the tappet accommodated in the recess in the arm when the type bar has been swung against the tension of its spring and intermittently engaged by the type bar to operate the ribbon-winding mechanism. 90
12. In a typewriter, a type-carrier including an arm, a type bar mounted on the arm for independent movement, a stop for limiting the movement of the type bar relative to the arm in one direction, a vibrative mechanism, an intermedium engaged with the vibrative mechanism when the type bar is in printing position to effect the intermittent actuation of the type bar in one direction against the tension of a spring which tends to urge the type bar in the opposite 95
13. In a typewriter, the combination with a type-carrier actuating mechanism, of a type-carrier including an arm operated by the carrier actuating mechanism, a type bar mounted on the arm for movement independently thereof, a spring for yieldingly re-

- direction, and a key-controlled lever for throwing the type carrier into position to effect the engagement of the intermedium and the vibrative mechanism.
- 5 29. In a typewriter, a type-carrier comprising an arm, a type bar mounted thereon for independent movement relative thereto, a tongue on the type bar to be engaged by a notched wheel, when the type-carrier is moved into printing position, to effect the intermittent actuation of the type bar outwardly, a spring placed under tension by the outward movement of the type bar to return the type bar to the printing point, an actuator for rotating the wheel, and a key-controlled lever for bringing the type carrier to printing position.
- 10 30. In a typewriter, a type-carrier comprising an arm, a type bar mounted thereon for independent movement, a vibrative mechanism operatively engaging the type bar when the carrier is moved to printing position, to repeatedly oscillate the type bar, a carriage-operated rack for actuating the vibrative mechanism, and a key-controlled lever for moving the type-carrier to printing position.
- 15 31. In a typewriter, a type-carrier comprising an arm, a type bar mounted thereon for independent movement, an intermedium on the type bar to be engaged by a rotatable member, when the type carrier is moved to printing position, to intermittently swing the type bar outwardly, a spring placed under tension by the outward movement of the type bar to return the type to the printing point, a pinion operatively connected with the rotatable member, a carriage-actuated rack for rotating the pinion, and a key-controlled lever for moving the type carrier to printing position.
- 20 32. In a typewriter, the combination with a power-driven carriage, an escapement, and a letter-spacing rack on the carriage, releasably engaging the escapement, of a type-carrier adapted to be yieldingly held in printing position, a pinion-operated vibrative mechanism for repeatedly oscillating the type-carrier to effect a series of successive type impressions, a rack on the carriage meshing with the pinion, and a key controlled lever for releasing the letter-spacing rack from the escapement and throwing the carrier to printing position.
- 25 33. In a typewriter, the combination with a power-driven carriage, an escapement, and a letter-spacing rack on the carriage releasably engaging the escapement, of a type-carrier yieldingly held in printing position, a pinion-operated vibrative mechanism for repeatedly oscillating the type-carrier to effect a series of successive impressions, an actuating rack on the carriage meshing with the pinion, and a key-controlled lever for releasing the letter-spacing rack from the escapement, meshing the actuating rack with the pinion, and for throwing the carrier to printing position.
- 30 34. In a typewriter, the combination with a power-driven carriage, an escapement, and a letter-spacing rack mounted to swing on the carriage for releasably engaging the escapement, of a yielding type-carrier, a pinion-operated vibrative mechanism for repeatedly oscillating the type carrier to effect a series of successive impressions, an actuating rack operatively connected with the letter-spacing rack to rock therewith, and a key-controlled lever for releasing the letter-spacing rack from its escapement and engaging the actuating rack with its pinion to operate the vibrative mechanism.
- 35 35. In a typewriter, the combination with a power-driven carriage, an escapement, a letter-spacing rack mounted on the carriage to releasably engage the escapement, and release mechanism for disengaging the rack from the escapement, of a key-controlled type-carrier, vibrative mechanism with which the carrier is engaged when in printing position for repeatedly oscillating the carrier to effect a series of successive impressions, and an independently operable lever actuated by the operation of the type-carrier key for effecting the release of the rack, as the type-carrier is thrown into printing position.
- 40 36. In a typewriter, the combination with a power-driven carriage, an escapement, a letter-spacing rack mounted on the carriage to releasably engage the escapement and release mechanism for disengaging the rack from the escapement, of a key-controlled type-carrier, and an independently operable lever actuated by the operation of the type-carrier key for effecting the release of the rack as the type-carrier is thrown into printing position.
- 45 37. In a typewriter, the combination with a ribbon-carrying spool, and a driving shaft for winding the ribbon on the spool, of a yielding type-carrier, vibrative mechanism for effecting the repeated oscillation of the type carrier when in printing position, a ratchet on the driving shaft, a pawl engaging the ratchet, and a tappet operatively connected with the pawl and intermittently engaged by the type-carrier, for driving the shaft.
- 50 38. In a typewriter, the combination with a ribbon-carrying spool, and a driving shaft for winding the ribbon on the spool, of a yielding type-carrier, vibrative mechanism for effecting the repeated oscillation of the type carrier when in printing position, a ratchet on the driving shaft, a swinging lever, to one end of which is operatively connected a ratchet-engaging pawl, the type-carrier intermittently engaging the opposite end of the lever to actuate the latter and the pawl.

against the tension of a spring, which returns the lever to normal position alternately with the engagement of the type-carrier therewith.

5 39. In a typewriter, the combination with a ribbon-carrying spool and a driving shaft for winding the ribbon on the spool, of a yielding type-carrier, vibrative mechanism for effecting the repeated oscillation of the 10 type-carrier, when in printing position, a ratchet on the driving shaft, a pawl engaging the ratchet, and a lever vibrated with the type carrier for driving the shaft.

15 40. In a typewriter, the combination with a ribbon-carrying spool and a driving shaft for winding the ribbon on the spool, of a yielding type-carrier, vibrative mechanism for effecting the repeated oscillation of the 20 type-carrier, when in printing position, a ratchet on the driving shaft, a swinging lever to one end of which is operatively connected a ratchet-engaging pawl, the type-carrier adapted to intermittently engage the 25 opposite end of the lever to actuate the latter and the pawl against the tension of a 30 spring, which returns the lever to normal position alternately with the engagement of the type-carrier therewith, and a guide having an inclined slot for permitting the lever to follow the ratchet through its travel.

35 41. In a typewriter, the combination with a carriage, of a type-carrier having a type, a finger-piece operatively connected with the type carrier for actuating the latter to the printing point, the type-carrier including an arm, and a type bar carried thereby and having an oscillatory movement independently of the arm, an intermedium projecting from the type bar, a rotatable member with which the intermedium engages and by which it is intermittently forced outward to swing the type bar in one direction, and a spring for returning the type bar to 40 normal position relative to the arm.

45 42. In a typewriter, the combination with a carriage, of a type-carrier having a type, a finger-piece for actuating the type-carrier to the printing point, the type-carrier including an arm, and a type bar carried thereby, and having an oscillatory movement independently of the arm, a tongue on the type bar, a star or cam wheel with which the tongue engages and by which it is intermittently forced outward to swing the type bar, and a spring for returning the type bar to normal position relative to the arm.

50 43. In a typewriting machine, the combination with a driven carriage having a 55 platen and an escapement and releasing device therefor, of a controlled mechanism including a type and a toothed wheel, a key for releasing the carriage from its escapement and causing it to turn said wheel, and 60 connections between said wheel and type

brought into operative relation by the operation of said key to cause the type to contact with the platen.

44. In a typewriting machine, the combination with a movable platen carriage and locking devices therefor, of a vibratory type-bar, mechanism actuated by the carriage in its travel for vibrating said type bar, and a key for releasing the carriage from its locking devices and also for moving the type 75 bar to printing position.

45. In a typewriting machine, the combination with a power driven carriage, a letter-feed mechanism controlling the carriage, a vibratory type, a vibrator therefor actuated by the movement of the carriage in the direction of its feed, and a single 80 manual device for controlling the vibrator and disconnecting said feed mechanism from the carriage.

46. In a typewriting machine, the combination with a power driven platen carriage and escapement mechanism, of a type-holding device, a reciprocator device operatively connected with the type-holding device, and a single means for placing said reciprocator device into operating position and releasing the carriage from the escapement; the reciprocator device being arranged to be actuated by the carriage when 95 it is released from the escapement.

47. In a typewriting machine, the combination with the carriage and escapement mechanism, of a vibrator device and a controlling mechanism, a movable type-holding 100 device operatively connected to both, said vibrator device being arranged to be actuated by the carriage when it is released from the escapement, and a key lever operable both to release the carriage from the escapement and to bring the vibrator device into operative relation to the carriage.

48. In a typewriting machine, the combination with the carriage and escapement mechanism, of a controlled reciprocating 110 means, said means actuating a type bar and being arranged to be actuated by the carriage when said carriage is released from the escapement, and a single key lever controlling the relation of both the escapement 115 mechanism and said reciprocating means to the carriage.

49. In a typewriting machine, the combination with the carriage and escapement mechanism and means for releasing the escapement, of a power driven type bar connected with driving mechanism actuated by the carriage when it is released from the escapement, and a single key controlling both said releasing means and said driving 120 mechanism.

50. In a typewriting machine, the combination with the carriage and escapement mechanism and means for releasing the escapement, of a power driven type bearing 125

- printing arm, power transmitting means, said means becoming operative when the carriage is released from the escapement, and a single device for operating the said releasing means and bringing said power-transmitting means into operative relation to the carriage.
51. In a typewriting machine, the combination with a carriage and escapement mechanism, of means for releasing the escapement, a type bar, type bar actuating means, a hand operated controlling means, and a power transmitting device, said type bar and transmitting device being moved into operative position and the carriage released from the escapement by said controlling means, the power being transmitted to the type bar when the carriage is released from the escapement.
52. In a typewriting machine, the combination with a power driven carriage, of a vibratory type, a vibrator therefor actuated by the movement of the carriage in the direction of its feed, and a single manual device for both bringing the vibrator into operative relation to the carriage and effecting the operation of the vibrator.
53. In a typewriting machine, the combination with a driven platen carriage and escapement mechanism therefor, of means for automatically actuating a typewriting mechanism, means for releasing the carriage from the escapement mechanism, and a single device for both operating said releasing means and moving said actuating mechanism into position to be operated by the carriage.
54. In a typewriting machine, the combination with a driven platen carriage and escapement mechanism, of means for producing a reciprocating motion when actuated, a type-holding device operatively connected with said reciprocating motion producing means, said type-holding device being adapted to hold separated the carriage and its escapement, and a controlling device to operate the type-holding device and release the carriage from the escapement, said elements being so arranged that the reciprocating motion producing means will be actuated when the carriage is released from the escapement.
55. In a typewriting machine, the combination with a carriage and escapement mechanism, of manual means for releasing the escapement, and an automatically actuated typewriting or printing device having operative connection with and controlled by said means for releasing the escapement.
56. In a typewriting machine, the combination with a carriage and an escapement mechanism, of a key lever operable to release the carriage from the escapement mechanism, a type-carrier, means to vibrate said carrier, and a second key lever operable to move the type-carrier into operative position and operate said first-named key lever.
57. In a typewriting machine, the combination of a carriage, means to supply power for operating the carriage, an escapement controlling the letter-feed of the carriage, a key to release the carriage from the escapement, a type-carrier, means operated by the carriage for vibrating said type-carrier, and a second key operable to move the type-carrier into operating position and operate the first-named key, said first-named key being operable independently of the second key.
58. In a typewriting machine, the combination of a carriage, means to operate the carriage, racks carried by the carriage, an escapement coöperating with one of said racks to control the letter feed, a second escapement coöperating with the other rack, a type-carrier adapted to be vibrated by said second escapement, and means to move said racks into and out of operative relation to the escapements.
59. In a typewriting machine, the combination with a carriage and means for operating the carriage, of a rack frame comprising racks, an escapement coöperating with one rack to control the letter feed, a pinion coöperating with the other rack, a type-carrier, means connected to said pinion to vibrate said type-carrier, and means to operate the rack frame to disengage the first rack from its escapement and connect the second rack to said pinion.
60. In a typewriting machine, the combination with a carriage and driving means therefor, of a rack frame comprising racks, escapement mechanism coöperating with one rack to control the letter feed of the carriage, a pinion to coöperate with the other rack, a type-carrier, means connected to said pinion to vibrate the type-carrier, a key lever, and connections with said key lever for swinging the rack frame to disengage the escapement mechanism and connect with said pinion and thereby cause the vibration of the type-carrier.
61. In a typewriting machine, the combination with a carriage and driving means therefor, of racks, an escapement coöperating with one rack to control the letter feed of the carriage, a type-carrier vibrator, a key lever, and connections therefrom to simultaneously move the racks to release said escapement and connect with the vibrator.
62. In a typewriting machine, the combination with a carriage and driving means, of escapement mechanism controlling the feed of the carriage, a rotary member provided with an annular series of cams, a type-carrier, elastic means for holding said carrier in engagement with said rotary member and thereby causing the carrier to be vibrated by the cams when said member is rotated, a key lever, and means operated there-

- by to move said type-carrier into operative position to connect said rotary member with the carriage to be driven thereby, and to disconnect the carriage from the escapement mechanism.
63. In a typewriting machine, the combination of a main type bar system, a carriage, and an auxiliary typewriting mechanism connected with the carriage for the purpose of controlling the movement of said carriage in the direction of its feed.
64. In a typewriter, in combination, a main system of type-bars, additional writ-

ing means including a finger key forward of the main body of the machine, mechanism 15 operatively connected with said key and said writing means and adapted to impart a plurality of printing strokes to said writing means when said key is continuously moved in one direction.
